UNITED STATES PATENT OFFICE.

ADOLPH F. KRUEGER, OF MILWAUKEE, WISCONSIN.

METHOD AND APPARATUS FOR ASSEMBLING CABINETS AND THE LIKE.

1,404,978.

Specification of Letters Patent. Patented Jan. 31, 1922.

Application filed August 19, 1920. Serial No. 404,669.

To all whom it may concern:

Be it known that I, ADOLPH F. KRUEGER, a citizen of the United States, and resident of Milwaukee, in the county of Milwaukee 5 and State of Wisconsin, have invented certain new and useful Improvements in Methods and Apparatus for Assembling Cabinets and the like; and I do hereby declare that the following is a full, clear, and exact description thereof.

My invention relates to new and useful improvements in the method and apparatus for assembling box or cabinet structures such as the type shown in my co-pending application 15 for patent on phonograph record storage cabinets, filed March 13, 1920, Serial No. 365562, and comprising a box body of the covered type having a series of partitions secured therein to form seats for a series of 20 slidable record-carrying sheets.

It is primarily an object of my invention to provide a method of assembling and securing the various partition and wall members of a cabinet structure of this character 25 in such manner as to effect a firm holding of the parts for their paste or other securement whereby to provide an article of maximum neatness and compactness, and it is more particularly my object in this connection to provide 30 a method of assembling the cabinet structure wherein all of the partition members are simultaneously secured in the wall members and held in their proper relative positions pending the fixation of the securing medium. A further primary object resides 35 in the provision of an apparatus for conveniently and expeditiously carrying out my improved method of forming articles of the present character.

In forming box or cabinet structures of the covered type, it has been heretofore customary to assemble the body members of the box or cabinet structure and to then apply the cover sheets thereto, in this connection 40 it is a further object of my invention to provide a method of forming such structures which utilizes valance portions of the cover flanges as the means for securing the body members of the box or cabinet together 45 in the initial assembly of the article.

A further and important object of my invention resides in the provision of an assembling apparatus for carrying out my improved method, which is provided with a

plurality of mechanisms for simultaneously 55 carrying out successive steps of the assembling operation whereby to facilitate the speed of operation of this character, and in this connection it is more particularly my object to provide an apparatus including a 60 series of assembling frames adapted to be selectively associated with the various clamping and charging portions of the apparatus.

A still further object resides in the provision of an assembly frame associated with 65 charging and clamping mechanisms and invertible to facilitate the application of top and bottom valance flanges to the respective casing portions.

A still further object resides in the provision of an assembly frame provided with 70 means for exerting clamping pressure in the plane of the frame against the edge portions of an article secured therein and also provided with means for exerting clamping 75 pressure transversely of the plane of the frame.

With the above and other objects and advantages in view, my invention resides more particularly in the novel combination, formation and arrangement of parts herein-after described and pointed out in the appended claims.

In the accompanying drawings—

Figure 1 is a plan view of an assembling 85 apparatus constituting one embodiment of my invention and providing a means for carrying out my improved assembling method;

Figure 2 is a longitudinal sectional view 90 through the apparatus;

Figure 3 is a transverse sectional view through one of the assembly frames in operative relation to the charging mechanism of the apparatus, the plane of this section 95 being indicated by the line 3—3 of Figure 1, and showing the various portions of a record cabinet mounted in the apparatus in initial position;

Figure 4 is a view similar to Figure 3, 100 but showing the partition sheets and spacer plates forced through the forming frame and assembled within the wall members held by the assembly frame;

Figure 5 is a view taken transversely 105 through one of the assembly frames in operative relation to its corresponding clamping mechanism prior to the application of

clamping pressure to an assembled cabinet held in the assembly frame;

Figure 6 is a similar view showing the application of clamping pressure;

5 Figure 7 is a plan view of one of the partition sheets of a cabinet constructed in accordance with my improved method;

10 Figure 8 is an elevational view of the rear wall member showing the cover sheet therefor secured thereto with its edges extended beyond the edges of the wall member to form attaching valance flanges;

15 Figure 9 is a similar view of one of the side wall members, and

20 Figure 10 is a transverse sectional view through the side wall member on a plane indicated by line 10—10 of Figure 9 and showing the valance flange structure for engagement with the forward edges of the top and bottom sheets of the cabinet.

25 Entering now into a brief description of my improved method and apparatus, my method resides essentially in building up a pile of alternate core plates and cabinet partition sheets provided with valance flanges, this pile being preferably formed in a supporting frame removable from the body of the apparatus, and in then applying wall members against the sides of the pile of core 30 plates and partition sheets, this action being carried out in my present apparatus by setting the wall members in an assembly frame located under a forming frame and in then forcing the pile of core-plates and partition sheets 35 through the forming frame and into the assembly frame, thus bending the valance flanges of the partition sheets, said assembly frame being provided with suitable clamping means. In the present apparatus, I pro-

40 vide a central charging mechanism including a removable support and forming frame, a hingedly mounted guide frame and a swinging plunger movable through said frames. At each side of the charging mechanism I 45 provide a clamping mechanism. A pair of assembly frames are provided which are pivoted between each clamping mechanism and the charging mechanism, which is thus common to both assembly frames, and the as-

50 semby frames may be swung alternately for operation with the charging mechanisms and their respective clamping mechanisms, each of the frames being inverted in this swinging movement to facilitate application of the top and bottom valance flanges of the casing structure, as will be later described in detail.

55 It will be also appreciated that by providing a pair of assembly frames, one of said frames may be held in the clamping mechanism for the proper duration of time while the charging operation is carried out with respect to the other frame, thus providing for a substantially continuous operation of the apparatus, which, together with the economy of 60 time effected by the novel method steps pro-

vides for an exceedingly rapid output of accurately and compactly formed cabinet articles.

70 My improved method and apparatus is utilized in the present illustrations for forming a phonograph record storage cabinet which, in detail Figures 6 to 10 and in the assembled relation of its parts in Figure 5, comprises a series of partition sheets *a* spaced apart a slight distance and each having three 75 side edge portions turned to provide attaching flanges *b* engageable with rear end and side wall members *c* and *d* respectively. Top and bottom sheets *e* and *f*, shown in black lines in Figure 5, are provided for the cabinet structure, and a cover and attaching sheet *g* is secured to the rear end wall *c*, with its edges projected past all of the edges of the rear end wall to form valance flanges, while a cover sheet *h* is secured to each side wall *d* 80 with its top and bottom edges projected beyond the corresponding edges of the side wall to form valance flanges, the forward edge of the sheeting *h* being bent about the forward edge of the side wall and slit at *i* at 85 its bend. The top and bottom valance flanges of the cover sheets are bent about and pasted to the top and bottom *e* and *f* of the cabinet, while the end valance flanges of the rear end wall are bent about and pasted to the side 90 walls, the inturned forward edge portion of the valance flange of the cover sheet *h* being pasted to the inner sides of the top and bottom *e* and *f* to form a neat and firm connection.

100

95 Referring now in specific detail to the structure shown in the drawings, there is provided a main support frame comprising upper longitudinal sills 10 supported by legs 11 and connected by end cross-sills 12, by an intermediate pair of cross-sills 13 and by a pair of clamp support cross-sills 14 at each side of the pair of intermediate sills 13. This main support frame also includes lower longitudinal sills 15 and cross-sills 16. A shelving 17 is mounted at the rear portion of the support frame to carry work material or other articles for the convenient use of the operator.

110

115 A pair of assembly frames is provided in the present apparatus and each of these frames is formed of side bars 18 connected by transverse bars 19, adjacent ends of the side bars being continued past the corresponding end bar 19 and secured on pivot 120 pins 20 carried by the side sill structure of the assembly frame and by diagonal brace members 21 whereby each of the frames is mounted to swing on a transverse axis located at the side of the centrally positioned 125 charging mechanism of the machine. A pair of clamping members 22 and 23 respectively are disposed in each assembly frame and located longitudinally of an adjacent pair of sides of the frame, each of said clamping 130

members being normally urged outwardly toward the side of the frame by retractile springs 24, while suitable cam means is provided for urging the clamping members 5 inwardly to exert clamping pressure in the general plane of the assembly frame, such cam means comprising in the present instance a cam head 25 secured to the clamping member and having inclined surfaces 10 co-operating with inclined surfaces of a clamping head 26 journaled on a bolt 27 in the adjacent side of the assembly frame, said clamping head 26 carrying an upstanding handle 28 to effect its operative movement. The other two mutually adjacent sides of the assembly frame have longitudinal strips 29 secured on their inner faces and these strips 29 in turn are provided with facings of leather 30 or similar material, said facings having their edges extended beyond the edges of the strips 29 and secured to the faces of top and bottom transverse clamping strips 31 whereby hinge connections are afforded between the 25 top and bottom clamping strips 31 and the respective strip 29. The adjacent ends of each pair of transverse clamping strips 31 are connected by a contractile coiled spring 32 in such manner that the points of connection of the springs are movable to either side of the hinge connections afforded for the strips whereby the strips may be resiliently held either in seating engagement against the edges of their corresponding intermediate strip 29, or may be urged in 35 inwardly swung position toward an article held in the frame, as shown at the right hand side of Figures 5 and 6. The clamping member 23 also carries a pair of transverse clamping strips designated at 31, whereby an article assembled in the clamping frame may in the present instance have transverse pressure exerted thereon at three sides thereof.

40 Taking up now the charging mechanism of the apparatus, it is noted that when one of the assembly frames is swung inwardly, the charging space of the frame is disposed over the intermediate cross-sills 13 and a guide and seating frame 33 is pivoted at the rear of the main support frame and adapted to swing downwardly over the assembly frame in this position, said guide frame being recessed along its upper side portions to receive the lower portion of a support and forming frame 34. Shield-plates 35 are secured to the inner faces of three sides of the guide frame and depend therebelow to extend into the forming frame, the lower edges of these plates being resiliently inclined inwardly. As shown in Figure 3, the wall members of the cabinet structure are set within the assembly frame when the same is in charging position and 45 the lower edge portions of the shield plates

35 cover the upper valance flange portions of the previously attached cover sheets for these walls, the walls being supported in proper position within the frame. The support and forming frame 34 carries angular upstanding guides 36 at its corners and three sides of the frame are provided with forming ledges 37 adapted to seat the lowermost of a pile of alternate partition sheets *a* and core sheets *x*, the dimensions of the core sheets being such as to snugly pass the ledges 37 of the forming frame and to bend the flange edge portions of the partition sheets *a* during their movement therepast. For forcing the pile of core and partition sheets 80 through the forming frame and into the assembly frame, a plunger head 38 is provided which is carried by a bar 39 slidably carried by a pair of arms 40 projecting from a turning post 41 which is supported by a standard 42 whereby the plunger may swing toward and away from operative position over the forming frame. This plunger is engaged by an operating lever 43 pivoted to the turn post 41 and resiliently urged upwardly to initial position by a contractile spring 44.

I will now describe in detail the complete operation of the charging mechanism to provide the assembly of the parts of the cabinet: One of the assembly frames is first swung to its central or charging position; the wall members *c* and *d* of the cabinet are then placed in the frame against the respective sides thereof; glue is then applied to the inner faces of the walls, said glue being preferably carried in a pot (not shown) which is disposed in a well under the assembly frame, seating on preferably an electric heater base 45, the switch buttons 46 for controlling this heater base being preferably mounted on the main support frame between the pivots of the guide frame 33; the guide and seating frame 33 is next 100 swung downwardly onto the assembly frame to shield the upper portions of the walls and valance flanges, and the support and forming frame is placed on the frame 33. It is incidentally noted that this support and forming frame is separate from the body of the apparatus, and a plurality of such frames may be used whereby an assistant may be loading alternate core-sheets and partition sheets in one of the forming frames while the operator of the apparatus is effecting a charging operation with another of the frames. The plunger 38 is then 105 swung over the pile of partitioning core sheets and depressed to force said sheets through the forming and guide frames and into the assembly frame, the flange edge portions of the partition sheets being turned in this operation for engagement with the inner faces of the walls to secure them in place by the paste previously applied to the 110

115 120 125 130

walls, it being noted that each flange portion of each partition sheet is confined between the respective wall and an edge portion of the corresponding rigid and relatively thick 5 core sheet α . The handles 28 of the clamping heads are then rocked to move the clamp members 22 and 23 inwardly, thus applying pressure against said walls in a general 10 longitudinal direction of the plane of the assembling frame. The forming frame 34 is then removed, the guide frame 33 is lifted and the bottom sheet f of the cabinet is placed on the pile of partition and core sheets, seating on the uppermost core sheet. 15 The upper transverse pressure strips 31 and 31^a are then swung inwardly, being retained in inwardly swung position by the movement of the points of connection of the coiled springs 32 past their hinge connections. It is noted that prior to application 20 of the bottom sheet f , the slit forward edge portions of the valance flange of the cover sheet h are bent inwardly as shown in dotted lines in Figure 10 for engagement 25 with the inner face of the bottom sheet.

The assembly frame, with the cabinet parts assembled therein, is next swung upwardly and over to its corresponding transverse clamping mechanism, being thus inverted during said movement. The top sheet e is then applied to the cabinet structure and the other transverse pressure strips 31 and 31^a are bent inwardly and held by this spring connection, the entire cabinet 30 structure being now completely assembled with the exception that the end valance flanges of the rear cover sheet g are to be bent inwardly and pasted, which is accomplished upon removing the article from the 35 machine, it being understood that the valance flanges of the cover sheets are coated with paste and may be wetted at any suitable time.

It is noted that in the operation of forcing the pile of core and partition sheets through the forming frame, a partition sheet is necessarily disposed at the bottom of the pile, and to hold this partition sheet snugly in place and facilitate the even movement 40 of the pile through the forming frame I provide a yieldable support frame 47 carried by the upper ends of slideable posts 48, this frame sliding between the intermediate cross-sills 13 and being resiliently urged upwardly by contractile coiled springs 49 secured to said sills 13 and to the lower ends of the posts 48. This frame is automatically held in lowered position to provide for proper clearances of swinging 45 frame movement by a clutch block 50 pivoted to the main support frame and engageable with one of the posts 48, being resiliently urged to such engagement by a coiled spring 51. In its upward limit of movement 50 the top of the yieldable frame 47 is

flush with the shaping ledge 37 of the forming frame 34, while in its lower limit of movement the top of the frame is substantially flush with the assembly frame seats for the wall members and hence forms a 70 stop for the downward movement of the plunger so as to accurately position the pile of core and partition sheets in the assembly frame, this downward limit of movement being adjustably determined by stop bars 52 75 carried by the posts 48 and engageable with a seat frame 53 surrounding the legs or posts 48, said seat frame being adjustably held by set-screws 54 carried by portions of the main support frame. 80

The clamping mechanism for each of the assembly frames comprises an upper swinging clamp frame 55 hinged at the rear portion of the main support frame and carrying a series of bars 56 in which are mounted 85 spring-urged bolts 57 having their heads engageable with clamping strips 31 and 31^a. A second frame 58 is slidably mounted in the main support frame under the position for the assembly frame, being adjustably supported by set-screws 59 carried by the transverse sills 14 and this frame 58 carries spring-urged bolts 60 having their heads engageable with the undermost transverse pressure strips 31 and 31^a. Means is provided 90 for exerting downward pressure on the upper clamping frame 55 which comprises in the present instance a pair of lever-bars 61 pivoted to outstanding arms 62 of the main frame and carrying hook-links 63 engageable with a transverse bar 64 of the frame 55 whereby upon downward movement of the levers 31, the desired pressure will be applied against the resilient action of the bolts 57 and 60, the parts locking in this position 100 by reason of the movement of the pivotal connections of the links past the pivots of the levers. Thus, one cabinet structure may be assembled and clamped and the operator may then proceed with the assembly and 105 clamping of a second cabinet structure, giving ample time for the first cabinet structure to set, whereupon the first cabinet structure may be removed from the device by disengaging the upper clamping frame 55 and 110 moving the clamp members 22 and 23 to retracted position.

While I have shown the charging mechanism of my machine as associated with a pair of assembling frames pivoted for movement toward and away therefrom, it will be appreciated that my machine embodies more broadly the idea of successive association of these charging mechanisms with any series 120 of assembling frames so that a continuous operation may be carried out, and by reason of this continuous operation, together with other novel features of my method and apparatus, I provide an exceedingly rapid and 125 conveniently operable means for forming 130

cabinet structures of various natures. It will be further noted that, by first securing the cover sheet sections of the cabinet or box to the wall members thereof, then placing 5 said wall members against the corresponding sides of a filler body constituted in the present instance by my pile of core and partition sheets, and finally bending the projected valance edge portions of the cover 10 sheets, I provide an exceedingly convenient and economical method of forming boxes or cabinets of the so-called "covered" type.

While I have described a preferred method of forming articles of the present character, 15 and while I have shown a preferred type of apparatus for carrying out this method, it will be appreciated that various changes and modifications of method steps or of structural relations may be employed to meet 20 differing conditions of use and manufacture without departing in any manner from the spirit of my invention as embodied in the appended claims.

What is claimed is:

- 25 1. An assembling apparatus including a charging mechanism having a plunger, a clamping mechanism, and an assembly frame movable for selective association with the charging mechanism and the clamping mechanism.
- 30 2. An assembling apparatus including a charging mechanism having a plunger, a clamping mechanism disposed at each side of the charging mechanism, and a pair of 35 movable assembly frames each adapted for association with a charging mechanism and with a respective clamping mechanism.
- 40 3. An assembling apparatus including a charging mechanism having a plunger, a clamping mechanism disposed at each side of the charging mechanism, and a pair of assembly frames each provided with a 45 pivotal mounting between the charging mechanism and one of the clamping mechanisms, each of said assembly frames being adapted for association with the charging mechanism and a respective clamping mechanism.
- 50 4. An assembling apparatus including a charging mechanism having a plunger, a clamping mechanism, an assembly frame movable for selective association with said charging mechanism and said clamping mechanism and adapted to receive clamping 55 pressure from said clamping mechanism transversely of its general plane, and means carried by the assembly frame for exerting clamping pressure longitudinally of its general plane.
- 60 5. An assembling apparatus including an assembly frame, a movable forming frame adapted for disposition over the assembly frame, and a swinging plunger member movable through the forming frame.
- 65 6. An assembling apparatus including a
- main support structure, a frame hinged to said main support structure, means carried by said frame for holding work material, a clamping frame hinged to said main support structure, an assembly frame movable 70 to seat on the main support structure adjacent either of the first named frames whereby said frames may be selectively swung downwardly over the assembly frame, means for imparting clamping pressure to the 75 clamping frame, and means for forcing work material through the other hinged frame.
7. An assembling apparatus including a main support structure, a hingedly mounted guide frame, an assembly frame adapted 80 to seat on the main support structure whereby said guide frame may be swung downwardly over the assembly frame, a work material support frame adapted to movably seat over the guide frame, and a plunger member carried by the main support structure and adapted to force work material through the guide and support frames into the assembling frame.
8. An assembling apparatus including a 90 main support structure, a movable assembly frame adapted to seat on said main support structure, a movable forming frame adapted for disposition over the assembly frame, a yieldable work material support 95 carried by said main support structure and adapted to yieldably extend through said frames to support work material, and a plunger movable through said forming frame to force work material therethrough 100 into the assembling frame.
9. An assembling apparatus including a main support structure, a movable assembly frame adapted to seat on said main support structure, a movable forming frame adapted 105 for disposition over the assembly frame, a yieldable work material support carried by said main support structure and adapted to yieldably extend through said frames to support work material, a plunger movable 110 through said forming frame to force work material therethrough into the assembling frame, and releasable means for holding said support member against movement.
10. An assembling apparatus including a 115 main support structure, a movable assembly frame adapted to seat on said main support structure, a movable forming frame adapted for disposition over the assembly frame, a yieldable work material support carried by 120 said main support structure and adapted to yieldably extend through said frames to support work material, a plunger movable through said forming frame to force work material therethrough into the assembling 125 frame, and means forming an adjustable stop limiting downward movement of said yieldable support member.
11. In an apparatus of the class described, an assembling mechanism including a frame, 130

means for mounting a filler body and wall members in the frame, pressure strips hingedly connected with side portions of the frame, and means for urging said pressure strips inwardly.

12. In an apparatus of the class described, an assembling mechanism including a frame, means for mounting a filler body and wall members in the frame, pressure strips hingedly connected with side portions of the frame, and springs connected with said pressure strips and movable to either side of the hinge axes of said strips to hold said strips in either pressure applying or retracted position.

13. In an apparatus of the class described, an assembling mechanism including a frame, means for mounting wall members in the frame, pressure strips hingedly connected with side portions of the frame, and springs each connected with an opposed pair of pressure strips and movable past the plane of the hinge connection of the pressure strips upon inward movement of the strips.

14. In an assembling apparatus, a frame, clamp side members mounted in said frame, means for moving said members inwardly to exert clamping pressure in a direction longitudinal of the plane of the frame, pressure strip mounted at side portions of the frame, and means for urging said pressure strips inwardly to exert pressure transversely of the frame.

15. In an assembling apparatus, opposed pressure-applying members, means for urging said members together, an assembly frame insertable between said pressure-applying members, and pressure strips hingedly connected with side portions of the frame and adapted to swing inwardly for engagement with the edge portions of an article held in the frame, said pressure strips being engageable by said pressure-applying members when the assembly frame is inserted between said members.

16. An assembling apparatus comprising means for supporting a pile of alternate partition and spacer sheets above said frame, means for forcing said pile of sheets through the forming frame to form flanges on the edges of the partition sheets, and means for applying walls to said flanges.

17. An assembling apparatus including an assembly frame adapted to receive wall portions in its sides, a forming frame disposed above the assembly frame, means for supporting a superposed pile of alternate spacer and partition sheets above the forming frame, and means for forcing said pile through the forming frame into the assembling frame to provide flanges on the edges of the partition sheets engageable with said walls.

18. An assembling apparatus including an assembly frame adapted to receive wall

portions in its sides, a forming frame disposed above the assembly frame, means for supporting a superposed pile of alternate spacer and partition sheets above the forming frame, means for forcing said sheets through the forming frame into the assembling frame to provide flanges on the edges of the partition sheets engageable with said walls, and clamp means associated with said assembly frame for clamping the walls against the partitions.

19. An assembly apparatus including a series of assembly frames selectively movable to receiving position, a forming frame adapted for disposition over each assembly frame in receiving position, means for supporting a superposed pile of alternate spacer and partition sheets above the forming frame, and means for forcing said pile through the forming frame into the assembling frame to provide flanges on the edges of the partition sheets engageable with said walls.

20. An assembling apparatus including a main support frame, a plurality of assembling frames hinged to the main support frames and each adapted to swing to a common receiving position, a forming frame adapted for disposition over each assembling frame in its receiving position, means for supporting a superposed pile of alternate spacer and partition sheets above the forming frame, and means for forcing said pile through the forming frame into the assembling frame to provide flanges on the edges of the partition sheets engageable with said walls.

21. An assembling apparatus including a main support frame, a plurality of wall receiving assembly frames selectively movable to a common receiving position, a frame hinged to the main support frame and movable to a position over said common receiving position for the assembly frames, a detachable frame for supporting superposed series of alternate spacer and partition sheets above the hinged frame, and means for forcing said sheets from the detachable frame through the hinged frame into the assembling frame to provide flanges on the edges of the partition sheets engageable with said walls.

22. An assembling machine including an invertible assembly frame, a forming frame associated with the assembly frame, means for mounting an alternate series of partition and spacer sheets at the mouth of the forming frame, means for supporting walls in the assembly frame, and means for forcing said sheets through the forming frame into the assembly frame.

23. An assembling machine including an invertible assembly frame, a forming frame associated with the assembly frame, means for mounting an alternate series of partition

and spacer sheets at the mouth of the forming frame, means for supporting walls in the assembly frame, means for forcing said sheets through the forming frame into the assembly frame, and means associated with each side of the assembly frame for clamping balance flanges of material against sheets held in the frame.

24. The method of forming a cabinet of the class described which consists in building an alternate pile of core-plates and partition sheets having attaching flanges, in then applying wall members for paste engagement under pressure against the flanges of the partition sheets, and finally removing the core sheets.

25. The method of forming a cabinet of the class described which consists in building a pile of alternate core plates and partition sheets having marginal flange portions, in forcing said pile through a forming frame to bend the flange portions of the sheets, and in then applying wall members for paste engagement under pressure with said flange portions and finally removing the core plates.

26. The method of forming a cabinet of the class described which consists in building an alternate pile of core-plates and partition sheets having attaching flange portions, in providing a clamping frame and a superposed forming frame, in lining said clamping frame with wall members, in forcing said pile through the forming frame into the clamping frame to bend the flange portions of the sheet, in then applying clamping pressure in the clamping frame to press said wall portions against the flange portions, and in subsequently relieving said clamping pressure and removing the core-plates.

27. The method of forming a cabinet of the class described which consists in building an alternate pile of core-plates and partition sheets having attaching flanges, in providing wall members having cover sheets attached thereto with the edges of said cover sheets extended past the edges of the wall members, in then pressing said wall members against the sides of the pile for paste

engagement under pressure with the flanges, in applying top and bottom sheets to the pile, in then bending said extended edge portions of the cover sheets into paste engagement with the top and bottom sheets, and in then relieving said pressure and removing the core-plates.

28. The method of forming a cabinet of the class described which consists in building an alternate pile of core-plates and partition sheets, in providing wall members having cover sheets secured thereto with the edges of the cover sheets projected past the edges of the wall members to provide valance flanges, in then applying the wall members against the sides of the pile of core plates and partition plates and bending the valance flange portions of the cover sheets inwardly about said pile, and in finally removing the core sheets.

29. The method of forming a cabinet of the class described which consists in building an alternate pile of core plates and partition sheets, in providing wall members and top and bottom sheets for said pile, in applying cover sheets to certain of said members with edges of said cover sheets projecting beyond the members to form valance flanges, in then applying the members to the faces of said pile, and in then bending the valance flanges about the other members to hold the parts assembled.

30. The method of forming a cabinet of the class described which consists in providing a filler body, in providing top, bottom and wall members, in securing cover sheets to certain of said members with edge portions of the cover sheets projecting beyond the members to form valance flanges, in applying said members to the faces of the filler body, and in then bending the valance portions of the cover sheets about the other members in paste engagement therewith to hold the structure assembled.

In testimony that I claim the foregoing I have hereunto set my hand at Milwaukee, in the county of Milwaukee and State of Wisconsin.

ADOLPH F. KRUEGER.
